UNITED STATES PATENT OFFICE.

GUY ARDIZZONI, OF NEW YORK, N. Y.

BINDING MACHINE.

1,420,677.

Specification of Letters Patent. Patented June 27, 1922.

Application filed February 15, 1921. Serial No. 445,187.

To all whom it may concern:

Be it known that I, GUY ARDIZZONI, a citizen of the United States, and resident of the city of New York, borough of Manhattan, in the county of New York and State of New York, have invented a new and Improved Binding Machine, of which the following is a full, clear, and exact description.

My invention relates to a binding machine, and aims to provide a device of this character, more particularly intended for use in connection with the binding of sausages and meat.

In the binding of meats, and more particularly sausages, it is a well appreciated fact that great difficulty has been experienced in performing this operation for the reason that it has been very difficult to apply the binding agent under proper tension, and with sufficient evenness, so that primarily, the binding element will not become disarranged and loosened in the subsequent handling of the meat, and also that the same may present a neat appearance.

A further defect in this connection has been experienced in that the expense incident to this operation has been rather high, as the operation was a comparatively slow one.

Having these defects in mind, I have constructed a binding machine which is more particularly adapted for use in connection with the binding of meats, such as sausages, and by means of which the binding element and meat may be readily manipulated to apply the proper tension to the former, so that the same may be properly retained upon the latter while holding the parts of the meat in proper position.

A further object of my invention is the provision of a device of this character in which the binding element will be disposed with extreme neatness upon the object being bound.

A still further object of my invention is the construction of a binding machine by means of which the operation of binding may be accomplished with a minimum of expenditure of time and energy.

Further objects of my invention will appear in the annexed specification and drawings, which latter present one practical embodiment of my invention, and in which—

Figure 1 is an end view of a machine constructed in accordance with my invention,

Figure 2 is a plan view thereof, and Figure 3 is an enlarged partly sectional end view of the device as illustrated in Figure 2.

In these views the reference numeral 5 indicates a table which may be suitably supported, as at 6 and which carries the apparatus providing the binding machine.

Referring now more particularly to Figure 2 it will be seen that the shaft 7, of any desirable nature is mounted between brackets 10, which brackets also provide suitable bearings, serving to rotatably support a second shaft 8 spaced from, and disposed parallel to the shaft 7.

A third shaft 9 is rotatably mounted in a bracket 11, provided for this purpose, and suitable means such as a gearing 12, secured to the ends of the shafts 8 and 9, cooperates with these shafts to impart movement to one of the same upon the second being rotated. Thus upon any suitable driving element, such as a hand crank 13 being actuated to rotate the beveled gear 14 meshing with a similar gear 15 affixed to the shaft 9, the shaft 8 will be rotated, as well as the shaft 9 for a purpose hereinafter more fully specified.

With a view of providing means serving to properly retain the sausage or element 16 to be bound, it will be noted that an impaling head 17 is affixed to the inner end of the shaft 9, and a second impaling head 18 is secured to a shaft rotatably mounted upon a bracket 19, which latter is longitudinally adjustable within a track 20, thus permitting of an adjustment of the gap between the impaling heads, to permit the latter to properly grip an element 16 of any desired size.

A roll of binding material, such as cord 21 may be rotatably supported below the table 5, and has its end extending upwardly through a slot 22 formed in the latter, which slot is of a length equal to the maximum distance to which the impaling heads 17 and 18 may be spaced from each other.

Now with a view of providing a proper guiding element for the binder 21, it will be noted that a bracket is utilized, which bracket has one of its ends 23 formed so as to provide an encircling element enveloping the shaft 7 along which it is slidably movable. It will also be noted that the bracket is provided with a cut out portion 24, at a point in its under face, which cut

out portion is formed with semi-circular threads, of a pitch equal to the threads of the worm 25 forming a part of the shaft 8.

The bracket may conveniently have its outer end terminate in a fork 26 between the prongs of which any suitable type of spring pressed guiding element 27 is mounted. Thus upon the shaft 8 being rotated the threads of the worm portion 25 of the latter will cause a movement on the part of the bracket carried by the shaft 7, and bearing against the shaft 8, which movement will be continued to a point at which rotation of the shaft 8 will cease, it being noted, however, that a stop 28 may conveniently be utilized to prevent too great a movement on the part of the bracket.

Also if the bracket is to be moved rapidly, this may be accomplished by swinging the outer end, i. e. the forked end of the same upwardly, so as to disengage the cut out portion 24 from the worm 25. Upon this being accomplished, it will be appreciated that the bracket may readily be moved longitudinally of the shaft 7 to any desired position.

Now assuming that the binding cord 21 has been threaded so that its end passes over the guide 27, which latter extends to a point adjacent the position occupied by 16, the element to be bound, and upon the driving medium, such as the crank 13 being actuated that the impaling head 17 will be rotated to effect a rotation of the element 16, which rotation will be in turn transmitted to the head 18, the latter having been adjusted to its proper position.

Also this rotation will be transmitted by the gearing 12 to the shaft 8, and will result in a movement in the manner illustrated, in dotted lines, in Figure 2, on the part of the bracket, thus resulting upon the cord 21 being secured to the element 16, and in the latter being spirally wound, as has also been indicated in dotted lines in Figure 2.

Subsequent to this action, the cord may be severed, and the bracket returned to its normal position, the element 16 being removed, and a new object to be bound substi-

tuted, subsequent to which the operation may be duplicated.

Thus I have provided a binding machine which is capable of efficiently binding any desired element, the members retaining the latter being capable of being adjusted to permit of any desired size of article being handled.

Obviously numerous modifications of structure might readily be resorted to without in the least departing from the spirit of my invention, which I claim as—

1. A binding machine, including a guide shaft, a bracket having one of its ends slidably encircling said guide shaft, a second shaft formed with a worm portion disposed parallel to said first named shaft, said bracket being formed with a cutout portion presenting semicircular screw threads, of a pitch corresponding to the threads of the worm, and adapted to be brought into engagement with the same, said bracket presenting a fork at its outer end, a pair of headed spring pressed guiding elements carried by said fork, rotatable impaling heads positioned to one side of said second shaft, and means for connecting one of said impaling heads to said second shaft.

2. A binding machine including a guide shaft, a bracket having one of its ends slidably encircling said guide shaft, a second shaft formed with a worm portion disposed parallel to said first named shaft, said bracket being formed with a cutout portion presenting semi-circular screw threads, of a pitch corresponding to the threads of the worm, and adapted to be brought into engagement with the same, said bracket presenting a fork at its outer end, a pair of spring pressed guiding elements carried by said fork, rotatable impaling heads positioned to one side of said second shaft, means for connecting one of said impaling heads to said second shaft, and means connected to one of said impaling heads for operating and synchronizing the movement of said secondary shaft and impaling heads.

GUY ARDIZZONI.
